UNITED STATES PATENT OFFICE.

EDGAR L. LONG, OF BALTIMORE, MARYLAND.

LUBRICATING SYSTEM FOR RAILWAY CARS.

Application filed October 15, 1923. Serial No. 668,642.

To all whom it may concern:

Be it known that EDGAR L. LONG, a citizen of the United States, residing at Baltimore, State of Maryland, has invented certain new and useful Improvements in Lubricating Systems for Railway Cars, of which the following is a specification.

This invention relates to new and useful improvements in lubricating systems for railway cars, and more particularly to a means for lubricating the journal boxes on the trucks of said cars.

The principal object of the present invention is to provide a lubricating system of the above mentioned character, wherein the oil is continuously circulating through the journal boxes while the car is in motion, thereby obviating the necessity of employing waste or other absorbent material in the journal boxes to hold the lubricant.

Another important object of the present invention is to provide a lubricating system of the above mentioned character, which includes a cooling means whereby the oil during the circulation thereof through the journal boxes will at predetermined times be cooled, thus insuring the proper lubrication of the journal boxes and preventing the overheating of the same.

A further object of the present invention is to provide a lubricating system of the above mentioned character which is adapted to be mounted on the truck of a railway car and operatively connected with the axles of the wheels on the truck whereby the pump forming a part of the lubricating system will be caused to operate simultaneously with the movement of the axles, thereby assuring a continuous circulation of the lubricating medium to the journal boxes while the car is in motion, means being associated with the pump for preventing the accidental return of the lubricating medium during the delivery thereof to the journal boxes.

Another important object of the invention is to provide a lubricating system of the above mentioned character wherein means is associated with the truck of a car for supporting the pump in an operative position thereon, thus permitting the device to be readily and easily accessible.

A still further object of the invention is to provide a lubricating system of the above mentioned character, which is simple in con-

struction, inexpensive, strong and durable, and further well adapted for the purposes for which it is designated.

Other objects and advantages of this invention will become apparent during the course of the following description.

In the accompanying drawings forming a part of this specification, and in which like numerals designate like parts throughout the same,—

Figure 1 is a side elevation of a truck of a railway car showing my invention in position thereon, one of the journal boxes of said truck being shown in section.

Figure 2 is a fragmentary plan view of the truck with my invention positioned thereon.

Figure 3 is a longitudinal section taken on line 3—3 of Fig. 2.

Figure 4 is a transverse section taken on line 4—4 of Fig. 2.

Figure 5 is a fragmentary sectional view taken on line 5—5 of Fig. 2, showing the bracket for supporting the cooling coil.

Figure 6 is a sectional view of the pump showing the valves therein.

Figure 7 is a detail perspective view of the pump supporting bracket.

In the drawings wherein for the purpose of illustration is shown the preferred embodiment of my invention, the letter A designates generally the truck of a railway car, the same comprising the axles B, the latter having the usual wheels C mounted on the outer ends thereof in the well known manner. The bolster is designated by the letter D and as the same is of the usual construction, it is not thought necessary to further describe the detailed construction of the same. Carried by the axles B on the outer ends thereof are the journal boxes E. As each journal box is of the same construction it is thought that the description of one will suffice for the description of all.

The journal box is provided in its upper portion with the vertically extending passage 1 and this passage is adapted to communicate with a similar passage 2 provided in the bearing 3 which extends partly around the reduced portion of the axle B. The lower portion of the journal box provides what I term as a reservoir and is designated by the numeral 4 in the drawings for receiving the oil or other lubricating me-

dium which has been delivered to the axle B in the manner as will be presently described.

Secured to the lower portion of the bolster D is the bracket 5, the latter having formed 5 at one end thereof the arcuate channel member 6, the construction of which is clearly illustrated in Fig. 7 of the drawings. This bracket is adapted to be supported by the bolster D in the manner as clearly illustrated in Fig. 3 of the drawings, and the purpose thereof is to provide a means for supporting the pump designated by the numeral 7. This pump comprises the complementary sections 8 and 9, respectively, 10 and these sections have their flanged portions secured together by any suitable fastening means such as is shown at 10 in the drawings.

The channel portion 6 of the bracket 5 when in position on the bolster D will be adapted to receive the flanged portions of 20 the bottom of the pump whereby the latter will be supported in a substantially rigid position on the truck and to further hold the pump in position on the truck, I have provided additional supporting brackets designated by the numeral 11. Extending transversely through the section 8 of the pump 7 is the shaft 12 and the outer end thereof is 25 adapted to be supported in the bracket 11 as is clearly shown in Fig. 2 of the drawings, the inner end of the shaft supporting the pump rotor 13. Carried by the outer end of the shaft 12 is the gear wheel 14 and this 30 gear wheel is adapted to mesh with a similar gear wheel 15 which is mounted on the axle B, it being understood that the gear wheel 15 is of such a construction as to permit the same to be readily placed around the axle 35 and to this end I have constructed the gear wheel 15 of two like parts or sections, the same being locked together on the axle B by means of the fastening means shown at 16 in the drawings. The purpose of providing 40 the gearing arrangement is to provide a means whereby the pump rotor 13 will be simultaneously rotated with the operation of the railway car upon which the truck A is associated and in which the axle B rotates.

Communicating with the section 9 of the pump 7 adjacent the pump member 13 therein is the pipe 17, the latter extending outwardly from the section 9 for a suitable distance, and communicating with a short section of pipe 18 such as is clearly illustrated 50 in Fig. 2 of the drawings. The pipes 17 and 18 are termed what I call suction pipes. The outer end of the pipe 18 is connected by a suitable coupling or nipple to the elongated 55 sections of pipes 19 and 20, respectively. The outer ends of the pipes 19 and 20 communicate with the bottom portions of the journal boxes E mounted on the opposite ends of the axles B, as is also clearly illustrated in Fig. 4 of the drawings. The pur-

pose of this arrangement will be more fully described later.

As is clearly illustrated in the drawings in Fig. 3 particularly, it will be seen that the shaft 12 and the pump rotor 13 supported on the inner end thereof in the sections 8 and 9, is disposed in a plane below the axle B, whereby the operation of the pump will at all times be positive and will furthermore create the proper suction therefor in causing the circulation of the lubricating medium therethrough. The section of piping 17 is adapted to be supported in the outer end of the bracket 11 which is mounted on the bolster D to assist in supporting the pump in an operative position on the truck. 70

Extending from the upper portion of the pump casing 7 is the outlet pipe 21. This pipe 21 is connected by any suitable means to the coil pipe 22 which extends substantially in a horizontal plane above the pump and in order that the coil 22 may be held in a horizontal plane, I provide the supporting brackets shown at 23 in Fig. 5 of the drawings. These supporting brackets are supported on the bolster D and have their outer free ends adapted to receive the coiled portions of the pipe 22 in the manner as is clearly illustrated in Fig. 5 of the drawings. 85 The purpose of providing the coil sections 22 is to provide what I term as a cooling means for my lubricating system. 95

The outlet end of the coil pipe 22 communicates with the pipes 24 and 25, which are connected thereto by means of a suitable connection shown at 26 in the drawings, and these pipes 24 and 25 extend longitudinally with respect to the axles B and communicate with the transversely extending pipe 27, which is disposed between the journal boxes E on both sides of the wheels C, in the manner as clearly illustrated in Fig. 2 of the drawings, and the pipe 27 has its outer ends communicating with the upper portions of the inlet pipes 28. These inlet pipes are in turn supported in the upper portions of the journal boxes and adapted to communicate with the inlet passage 1. 100

A valve 29 is located in the coil pipe 22 adjacent the outlet end thereof for the purpose of cutting off the supply to the pipes 24 and 25 and a similar valve 30 is positioned adjacent the inlet end of the coil pipe 22, as is clearly illustrated in Fig. 2 of the drawings. Extending between the outlet pipe 21 and the pipe 24 is the by-pass 31 and a valve 32 is provided therein adjacent the pipe 24. The purpose of this pipe will also be more fully described in the following 105 paragraphs.

Communicating with the outer ends of the pipes 19 and 20 are the transversely extending pipes 33, the latter having communication with the bottom of each journal box E, 110 in the manner as clearly shown in Fig. 2 of 115

the drawings, whereby a complete circulating system is provided between the journal boxes E and the pump 7.

The operation of my lubricating system 5 may be briefly described as follows:—In the summer time, the valves 30 and 29 are opened and the valve 32 in the by-pass pipe 31 is closed. With the parts arranged as shown in the drawings, it will be seen that 10 when the car is in motion the rotation of the axle B will cause the consequent rotation of the gear wheel 14 mounted on the shaft 12, whereby the pump rotor 13 will simultaneously be operated and cause the suction of 15 the oil in the journal boxes E through the pipes 33 and the pipes 19 and 20 into the inlet pipes 18 and 17, and finally into the pump casing 7 where the pump rotor 13 will force the same through one of the passages therein, and past either of the valves 34 shown in 20 Fig. 6 of the drawings, and depending upon the direction in which the car is travelling, up through the outlet pipe 21. The oil passing through the outlet pipe 21 will be delivered through the coiled portions 22 where 25 the same will be permitted to expand and then through the pipes 27 into the upper portions of the journal boxes, where the oil will be finally discharged through the passages 1 and 2, onto the axles B, thus providing for a continuous circulation of the lubricating oil and obviating the necessity of having to employ waste or other absorbent material as is now commonly used and 30 placed in the bottoms of the journal boxes to hold the lubricant therein.

In the winter time the cooling of the lubricating oil by having the same pass through the cooled portions 22 may be eliminated by 35 closing the valves 29 and 30 and opening the valve 32, whereby the oil will be caused to pass from the pump through the outlet pipe 21 into the by-pass pipe 31 and be delivered to the journal boxes, in the manner as heretofore described. However, the circulation of the oil through the by-pass pipe 31 will also provide for the continuous circulation thereof in the same manner as when the coiled portions are in use.

50 It will thus be seen from the foregoing description that a lubricating system for a railway car has been provided wherein the journal boxes will be continuously lubricated during the movement of the car and furthermore a constant circulation of the lubricating medium will be obtained. The facility with which my device is placed in position upon the truck of a railway car will enable

a person to have ready access thereto whenever it is necessary to repair or control any 60 of the parts or valves thereof and it will not require the alteration or addition of parts to the body of the car in order to place my lubricating system in position on the truck.

From the foregoing description of the construction of my improved apparatus, it will be seen that I have provided a simple, inexpensive and efficient means for carrying out the objects of the invention, and while I have particularly described the elements best 70 adapted to perform the functions set forth, it is obvious that various changes in form, proportion, and in the minor details of construction may be resorted to, without departing from the spirit or sacrificing any 75 of the principles of the invention.

Having thus described my invention, what I claim as new and desire to secure by Letters Patent is:—

1. The combination with the truck of a 80 car including the axles and the journal boxes therefor; of a lubricating system associated therewith comprising a pump, a shaft extending transversely through said pump, a gear wheel mounted on the outer end thereof, an additional gear wheel mounted on one of said axles and adapted to mesh with said first mentioned gear wheel whereby said pump is driven simultaneously with the rotation of said axles, an oil delivery pipe connecting said pump to the journal boxes, a cooling coil associated with said delivery pipe, a by-pass pipe associated with said delivery pipe, valves for said coil and said by-pass pipe, and a return pipe between 90 said journal boxes and said pump.

2. The combination with the truck of a 100 car including the bolster, axles and journal boxes for the latter; of a lubricating system associated therewith comprising a pump, means on said bolster for supporting said pump, means associated with one of said axles and said pump for operating the latter simultaneously with the rotation of said axle, an oil delivery pipe connecting said pump to said journal boxes, a cooling coil associated with said delivery pipe and extending in a substantially horizontal plane, brackets carried by said bolster for supporting said cooling coil, valves associated 105 with said cooling coil, a by-pass pipe provided in said delivery pipe, a valve therein, and a return pipe between said journal boxes and said pump.

In testimony whereof I affix my signature.
EDGAR L. LONG.
